FREQUENCY CONTROL IN ULTRA HIGH FREQUENCY CIRCUIT

Charles Norman Smyth, London, England, assignor, by mesne assignments, to International Standard Electric Corporation, New York, N. Y., a corporation of Delaware

Application December 8, 1943, Serial No. 513,355
In Great Britain February 20, 1940

7 Claims. (Cl. 250—36)

This invention relates to thermionic ultra-high-frequency oscillation generators of the kind having a variable tuned regenerative feedback circuit between the anode and control grid and consisting of distributed impedances such as Lecher wires, co-axial lines and hollow resonators as opposed to tuned circuits comprising lumped inductances and lumped capacity.

In such apparatus it is usually desirable to be able to adjust the frequency of the tuned circuit to adjust the oscillation frequency to precise predetermined values or to vary the frequency automatically or otherwise by very small amounts.

It is already known to vary an oscillation frequency by altering the operating potentials of a thermionic valve coupled to the tuned circuit. It has also been proposed for frequency control or frequency adjustment to vary the dielectric constant in a capacity element in a tuned circuit by varying the electronic space charge set up between two electrodes connected to the Lecher wires of a tuned circuit. It is now proposed for frequency control or frequency adjustment of an oscillation generator of the type specified to vary in the tuned circuit with distributed impedances the dielectric constant of said distributed impedances while maintaining the permeability substantially constant. This may be done by varying the distribution and/or density of an electronic space charge set up between the conductors or conducting parts having the distributed impedances.

In one form of the invention the tuned circuit comprises a pair of Lecher wires varied in effective electrical length and characteristic impedance by means of the space charge in a vacuum tube. The vacuum tube has two parallel conductors sealed in its envelope and these conductors are arranged as parts of or extensions to the Lecher wires. Between the conductors in the vacuum tube are disposed electrodes for setting up a variable space charge. These electrodes normally comprise a thermionic cathode and a grid system. Alteration of the potential upon the grid or one of the grids in the grid system or the potential upon the conductors of the Lecher system has the effect of varying the intensity or the distribution of the space charge of electrons in the tube. Hence the effective capacity between the parts or extensions of the Lecher wires within the vacuum tube is varied. Although the capacity is varied due to the change in electron distribution, the inductance of the Lecher system remains substantially unaffected, since the permeability of the dielectric and the effective diameter of the wires are substantially unchanged.

The invention will be made clearer in the following description of one practical embodiment of the invention illustrated diagrammatically in the accompanying drawing comprising a single figure.

Referring to the drawing, an ultra-high frequency oscillation generator is indicated at OSC and comprises a thermionic valve V having a tuned circuit connected between the anode A and grid G. This tuned circuit comprises Lecher wires positioned parallel to each other and each wire is composed of two parts L1, L3 coupled by condenser C1 and L2, L4 coupled by condenser C2. The high tension voltage to the anode is obtained via the H. T. + terminal and the Lecher wire L1, and grid bias is obtained for the control grid by means of resistance R1 in the grid-cathode circuit. This oscillator circuit is of known type and it is considered unnecessary to give any further description in detail herein.

In accordance with the invention the frequency of the generator OSC is controlled by varying in effect the electrical length of the Lecher wires by means of a space charge. For this purpose the vacuum tube T is provided. This tube consists of a cathode K, control grid G1, screen grid G2 and the Lecher wires L3, L4 already referred to. These parallel conductors L3, L4 are sealed in the envelope of the tube T, and between them in the vacuum tube are disposed the electrodes, K, G1 and G2 for setting up a variable space charge. The cathode K is shown as indirectly heated from an alternating source of current. The Lecher wires L3, L4 are biased sufficiently negative through resistance R by a potential applied at B3 to prevent them from drawing current during any part of the high frequency cycle. The screen grid G2 is maintained at a positive potential by a potential applied at B1, while the control grid G1 is kept at a negative potential by a potential applied at B2. A space charge is developed between the screen grid and the Lecher wires and depends upon the potentials on the grids or the potentials upon the conductors of the Lecher system; the effective capacity between the Lecher wires is dependent upon this space charge and may thus be varied by varying the potentials on the screen grid or control grid or the Lecher wires or more than one of these members, thereby altering the tuning of the anode-grid circuit of the oscillation generator OSC and therefore the frequency generated.

The arrangement is particularly suitable for automatic frequency regulation since a voltage varying in accordance with fluctuations in fre-

quency, temperature or other variable and derived in any known manner can be applied to an appropriate electrode in the vacuum tube T to regulate the resonant frequency of the Lecher system.

For example, for automatic frequency correction in a radio receiver or other high frequency channel utilising the superheterodyne principle, one of the known forms of frequency error detector may be employed to derive a correcting voltage which in turn is applied in the manner described to change the oscillator frequency to correct the intermediate frequency.

In some cases the Lecher wires may lie wholly outside the vacuum tube but losses then arise due to the presence of the glass bulb in the dielectric space between the conductors.

Similar effects may also be obtained by the provision of a thermionic cathode, with or without other electrodes, within a resonator of the hollow type, the resonator being evacuated, or being enclosed in an evacuated bulb. Normally, such cathode and any associated electrode are distinct and separate from any thermionic system provided for the excitation of the resonator.

What is claimed is:

1. A thermionic ultra-high-frequency oscillation generator of the kind comprising a tuned regenerative feedback circuit between the anode and control grid consisting of distributed impedances, including means for setting up an electronic space charge between at least two portions of said distributed impedances, said means being separated from said impedances, and means for varying the distribution of said electronic space charge, whereby the frequency exhibited by said generator is correspondingly varied.

2. Oscillation generator employing distributed impedance elements to determine frequency, including means for setting up an electronic space charge between at least two portions of said distributed impedances, said means being separated from said impedances, and means for varying the density of said electronic space charge, whereby the frequency exhibited by said generator is correspondingly varied.

3. Oscillation generator according to claim 1, in which said tuned circuit comprises a pair of Lecher wires and including a vacuum tube arranged so that said Lecher wires extend at least in part into operative juxtaposition therewith but spaced from the electrodes thereof, said vacuum tube including means for varying the effective space charge between said Lecher wires.

4. Oscillation generator employing Lecher wires for frequency determination and including a vacuum tube arranged so that said Lecher wires extend at least in part into the interior of said tube but spaced from the electrodes thereof, said vacuum tube including means for varying the effective space charge between said Lecher wires.

5. Oscillation generator according to claim 4, and also including a co-axial group of electrodes for producing said space charge, located between the two conductors of said Lecher system, whereby the space charge is varied by varying the potential on at least one of said electrodes.

6. Oscillation generator according to claim 2, in which said distributed impedances comprise Lecher wires and also including a space charge vacuum tube, said Lecher wires extending at least partly outside said vacuum tube but closely adjacent to the walls thereof, whereby alteration of the space charge within said tube produces alteration of the effective capacity between the portions of said Lecher wires adjacent to said vacuum tube.

7. Oscillation generator according to claim 1, in which said distributed impedances comprise Lecher wires and also including a space charge vacuum tube, said Lecher wires extending at least partly within said vacuum tube, said tube including within the envelope thereof a co-axial electrode structure comprising an axial cathode and a co-axial grid system and two rods sealed in the envelope to extend parallel to each other along opposite sides of the electrode structure, said electrode structure affording control of said electronic space charge and said rods acting as internal extensions of said Lecher wires.

CHARLES NORMAN SMYTH.
